UNITED STATES PATENT OFFICE.

CHARLES E. NIXON, OF COLUMBUS, OHIO.

DESIGN FOR A FRATERNITY-PIN.

45,238.

Specification for Design.

Patented Feb. 10, 1914.

Application filed December 8, 1913. Serial No. 805,471. Term of patent 14 years.

To all whom it may concern:

Be it known that I, CHARLES E. NIXON, a citizen of the United States, residing at Columbus, in the county of Franklin and State of Ohio, have invented a new, original, and ornamental Design for Fraternity-Pins, of which the following is a specification, reference being had to the accompanying drawing, forming part thereof.

In the drawing Figure 1 is a plan view

of a fraternity pin, showing my new design; and Fig. 2 is a side elevation of the same.

I claim:

The ornamental design for a fraternity pin, as shown.

CHAS. E. NIXON.
